HEAT EXCHANGE APPARATUS AND
SUPPORT THEREFOR

Benjamin G. Newhall, Little Falls, N. Y., assignor
to Cherry-Burrell Corporation, Wilmington,
Del., a corporation

Application February 24, 1947, Serial No. 730,640

4 Claims. (Cl. 257—245)

1

This invention relates to apparatus, such, for example, as plate type heat exchangers, filter presses and the like, in which a plurality of plate-like elements or plate-like elements and spacers or frame-like elements are operatively supported in a press in close juxtaposition. More particularly, this invention relates to the novel improvements in the arrangement and construction of the supporting framework and the plate-like elements for the support of plate-like elements during operation of the device and for the support of the plate-like elements during the cleaning of the device and for the ready removal of the plate-like elements for inspection or replacement thereof.

This invention is particularly well adapted for use in connection with a plate type heat exchanger of the class commonly used in the processing of milk and like foods and similar products. The preferred embodiment of this invention will, therefore, be described, without, however, being limited thereto, in connection with the adaptation thereof in a sanitarily designed plate type heat exchanger of the class used in dairies for the heat treatment of milk and other dairy products.

Plate type heat exchangers commercially used in dairies are preferably made of stainless metals which adds appreciably to the cost and usefulness of the device. Attainment of satisfactory heat exchange efficiency between the heat exchange media requires the use of relatively thin metal in the plate-like elements and the operation of the device under reasonably rapid flow conditions and associated reasonably high pressures within the heat exchange media. Sanitary processing of food products requires the frequent inspection and cleaning of the individual plates and other elements of the device which come into contact with the food being processed.

It is, therefore, the primary object of this invention to provide a new and novel arrangement for a plate type heat exchanger or like device; in which the plate-like elements are slidably supported on and locked to the supporting frame; in which the individual plate-like elements when in operative position are supported upon a main support element; in which the individual plate-like elements may readily be moved from operative position to a position in which they may easily be inspected or cleaned and in which they are supported independently of other plate-like elements upon a main support and stabilized against excessive lateral and transverse tilting by stabilizing or auxiliary supports; and in which the plate-like elements may easily be removed from the press or frame for further inspection, cleaning and replacement; and in which plate-

2

like elements may easily be replaced and reinserted into the press and arranged into operative position.

Other objects and advantages of the present invention will be pointed out and more fully described in the following description when read in connection with the accompanying drawings, in which:

Figure 1 is a front elevational view of an improved plate-like element for a plate type heat exchanger embodying the present invention.

Figure 2 is a sectional view taken along the line 2—2 of Figure 1 of the drawings.

Figures 3 and 4 are explanatory views illustrating the procedure to be followed in removing plate-like elements from a press or frame of a plate type heat exchanger embodying the present invention.

Figure 5 is a side view of a plate type heat exchanger embodying the present invention, in which the plate-like elements and compression elements are assembled into the supporting framework.

Referring to the drawings, in which like elements are identified by like numerals, 10 and 11 represent the vertical risers or base elements of the plate heat exchanger frame or press, which includes a transverse and horizontally disposed support rod 12, auxiliary stabilizing and support rod 13, and auxiliary support and stabilizing rod 14, all securely fixed together to form a rigid frame.

A suitable number of plates or plate-like elements, generally identified by the numeral 15, when in operative position are supported upon the support rod 12 in the manner illustrated in Figure 5 of the drawings and stabilized by rod 13. In that position they are compressed between the adjacent face of the vertical riser 10 of the framework, the compression element 16 and header or spacing elements 17. The compression element 16 and the spacing elements 17 are slidably supported upon and stabilized by the rods 12 and 13. The auxiliary support rod 14 extends through suitable openings therein. Each of these rods 12 and 13, in turn, is provided at its free end with handwheels 18, threaded thereto. Suitable sleeve members 19, telescoped over the rods 12 and 13 and extending through appropriate bushings 20 in the front vertical riser 11, are utilized to apply compressive force against the compression element 16 and in turn against the assembled plates 15 and spacing elements 17. By that arrangement it is possible to maintain the individually movable plates 15, spacing elements 17 and compression element 16 in desired operative relation with respect to one another. In a conventional manner the left vertical riser 10, the compression

3

member 16 and the spacing elements 17 are provided with suitable connections, whereby the various heat exchange media may be introduced into the flow spaces formed intermediate the supporting framework.

Each of the plates or plate-like elements 15 is provided with an opposed set of peripheral slots 20 and 21 along its vertical axis. A second set of peripheral slots 22 and 23 is arranged, so that a line passing through the second set of peripheral slots 22 and 23 intersects a line joining the first set of peripheral slots 20 and 21. When the plates are in operative position, each of the slots of the second set of peripheral slots 22 and 23 is angularly disposed with respect to the vertical axis of the associated plate 15 or a vertical line passing through the stabilizing and auxiliary support rod 14 at the point of engagement between the rod 14 and the plate 15. In the preferred embodiment of the invention, the slots 22 and 23 are also angularly disposed or inclined with respect to a plane passing through the support rod 12 and the auxiliary support and stabilizing rod 13. Each of the slots 22 and 23 are also so positioned with respect to the adjacent slot 20 or 21, respectively, as to form a hook-like element 24, intermediate the adjacent slots. The hook-like element 24 is provided with a shank 25 and a head 26. The shank element 25 of the hook-like element 24 is of a width slightly less than the spacing between the auxiliary support and stabilizing shaft 13 and the stabilizing and auxiliary support shaft 14 spaced slightly therefrom. The head 26 of the hook-like element 24 is of a width appreciably in excess of the width of the shank 25 of the hook-like element 24.

By this construction, as is clearly illustrated in Figure 4 of the drawings, the hook-like element 24 of each of the plates 15, when coacting with the stabilizing rod 13 and the plate restraining or stabilizing and auxiliary support rod 14, forms a disengageable hinge-like element or stabilizer for disengageably supporting the plates 15 when they have been disengaged from the primary support rod 12 or to stabilize the upper portion of an individual plate against excessive lateral tilting when the plate is supported for cleaning upon the lower rod 12 out of contact with the remaining plates. In this latter position the plate is stabilized against transverse motion by the engagement of the rods 12 and 13 in the slots 20 and 21. In the preferred construction of the apparatus, the diameter of the substantially circular end of the slots 22 and 23 may be of a diameter of approximately $\frac{5}{8}$ of an inch to $\frac{3}{4}$ of an inch, while the diameter of the stabilizing and auxiliary support rod or plate-restraining rod 14 may be of a diameter of approximately $\frac{1}{2}$ of an inch to 1 inch. These dimensions are given only as examples and are not intended as limitations. The configuration of the portion of the hook-like element 24 adjacent the auxiliary support and stabilizing rod 13 must be such as to permit the lateral swinging of the plate 15 when hingedly supported by the hook 24 in cooperation with the rods 13 and 14. The possible swinging motion of the plate 15 must be sufficient to permit the disengagement of the hook-like element from the rod 14 after the contact between the hook-like element and the rod 13 has been lost. The clearance between the slots 20, 21 and 23 and the rods 12, 13 and 14 must be sufficient to permit the easy lateral shifting of the plates when compression has been released to enable the ready spacing of the plates for cleaning.

4

To remove a plate 15 from the supporting framework of a plate type heat exchanger, as illustrated by the drawings, it is first necessary to suitably rotate the handwheels 18 to release the compression upon the compression element 16, and thereafter separate the plates 15 and spacing element 17 and compression element 16 in a manner as clearly illustrated in Figure 3 of the drawings, and to a degree sufficient to permit the hereinafter described plate removal operation. Having thus separated the plates 15 and spacing element 17 a sufficient distance, a plate 15 is pivoted transversely with respect to the remaining assembly plates, in a manner as indicated by the arrow in Figure 3 of the drawings, until the slot 20 at the lower portion of the plate 15 is clear of the primary support rod 12. After the plate 15 has thus been cleared at its lower extremity from engagement with the support rod 12, it is then pivoted laterally with respect to the remaining assembled plates, as illustrated in Figure 4 of the drawings. In this lateral pivoted position, the pivoted plate 15 is supported by the disengageable hinge formed by the coaction of the hook-like element 24 and the rods 13 and 14. If it is desired to clean or inspect the plate while in this position, this may then be done by a workman by stabilizing the plate in the laterally pivoted position, as just described and as indicated in Figure 4 of the drawings.

To remove one or more plates from the supporting framework or press it is necessary only to pivot each of the plates 15 to be removed on its respective hook-like element 24 a sufficient distance until the shank 25 and head 26 of the hook-like elements 24 have cleared the stabilizing rod 13, whereupon the hook-like elements 24 may then be completely disengaged from the auxiliary supporting rod or restraining rod 14 by moving the plate in such a fashion as to withdraw the rod 13 through the outer opening in the peripheral slot 23. To insert one or more plates 15 into the supporting press or frame, the reverse of the operation just given for the removal of a plate from the press is followed.

As will be apparent from the drawings, the proportioning of the slots 20 and 21 and the relative size of the supporting rods 12 and 13 are such that when the plates 15 are in operative position in the supporting framework or press of the plate type heat exchanger, each of the plates 15 rests entirely on the primary supporting rod 12, with the lower slot 20 overlapping the sides and top of the rod 12. The stabilizing and auxiliary support rod 13 is so engaged in the slot 21 as to suitably stabilize the plates 15 against transverse tilting and as to assure the registration of the associate gaskets 27 and corresponding embossed ridges 28 of the juxtaposed, relatively flat plate-like elements 15 of the plate type heat exchanger.

The disengageable hinging and stabilizing of each of the plate-like elements 15 at corresponding ends of the plate-like elements 15 to the stabilizing and auxiliary support rod 13 and auxiliary support and stabilizing rod 14 provides a construction, in which each of the plate-like elements of the plate type heat exchanger may be separately removed from the supporting framework or press without necessitating the removal of the remaining plate-like elements, spacing elements or compression element. Likewise, each of the disengageably hinged plate-like elements may be individually swung laterally with respect to the remaining plates to permit the ready inspection

and cleaning of the separate plates. In similar manner, each of the plates 15, when plate compression has been released, may be separated from the remaining plates by sliding upon the support rod 12, whereupon it will sustain itself in stabilized position upon rod 12 without excessive lateral tilting or transverse tilting due to the engagement of the auxiliary support and stabilizing rods 13 and 14 in the slots 21 and 23.

It will be appreciated that in devices embodying the present invention the supporting rods may readily be arranged in substantially the same horizontal plane instead of being arranged in substantially the same vertical plane, as illustrated in the drawings of the preferred embodiment. Similarly, it will immediately be obvious to those skilled in the art that means other than rods as, for example, tubing, angle irons, bars, etc., may readily be substituted for the supporting rods referred to in the description of the preferred embodiment of the invention. Accordingly, it is desired that this invention should not be limited to the specifically described vertical arrangement of plate-like elements and supporting rod or member arrangement.

Having thus described the illustrated and preferred embodiment of this invention in a plate type apparatus, the invention is not to be restricted to the specifically illustrated embodiment thereof, as set forth in the drawings and as heretofore described, excepting insofar as necessary by the prior art disclosures and by the appended claims.

The invention is hereby claimed as follows:

1. A device of the type described comprising, in combination, a primary support means, a stabilizing means spaced from said primary support means, an auxiliary support means spaced from said stabilizing means and spaced from said primary support means, a plate-like element supported upon said primary support means and engaged for stabilization by said stabilizing means, and hanger means formed on said plate-like element and extending intermediate said stabilizing means and said auxiliary support means, said hanger means including a shank-like element having a width substantially equal to the distance between said stabilizing means and said auxiliary support means and a head element having a width substantially in excess of the width of said shank-like element.

2. In a device of the class described comprising a primary support member, a stabilizing member spaced therefrom, and an auxiliary support member spaced laterally from said stabilizing member and having a plurality of plate-like elements engageable between said primary support member and said stabilizing member, a plate-like element having a hook-shaped portion to engage said auxiliary support member whereby said plate-like element may be suspended from said auxiliary support member by engagement therewith, said hook-shaped portion comprising a shank interposed between said stabilizing member and said auxiliary support member and being of slightly less width than the distance between said stabilizing member and said auxiliary support member and having a head of greater width than said shank.

3. In a device of the class described comprising a primary support member, a stabilizing member spaced therefrom, and an auxiliary support member spaced laterally from said stabilizing member and having a plurality of plate-like elements engageable between said primary support mem-

ber and said stabilizing member, a plate-like element having a hook-shaped portion to engage said auxiliary support member whereby said plate-like element may be suspended from said auxiliary support member by engagement therewith, said hook-shaped portion comprising a shank interposed between said stabilizing member and said auxiliary support member and being of slightly less width than the distance between said stabilizing member and said auxiliary support member and having a head of greater width than said shank, said plate-like element being provided with straight peripheral notches in its upper and lower edges for engagement with said stabilizing member and said primary support member, respectively, and having a substantially arcuate slot formed in the upper edge thereof, said slot and said straight peripheral notch in the upper edge of said plate-like element defining said hook-shaped portion therebetween.

4. In a device of the class described comprising a primary support member, a stabilizing member spaced therefrom, and an auxiliary support member spaced laterally from said stabilizing member and having a plurality of plate-like elements engageable between said primary support member and said stabilizing member, a plate-like element having a hook-shaped portion to engage said auxiliary support member whereby said plate-like element may be suspended from said auxiliary support member by engagement therewith, said hook-shaped portion comprising a shank interposed between said stabilizing member and said auxiliary support member and being of a slightly less width than the distance between said stabilizing member and said auxiliary support member and having a head of greater width than said shank, said plate-like element being provided with peripheral notches in its upper and lower edges for engagement with said stabilizing member and said primary support member, respectively, and having a substantially arcuate slot formed in the upper edge thereof, said slot and said peripheral notch in the upper edge of said plate-like element defining said hook-shaped portion therebetween, said primary support member and said stabilizing member engaging the respective notches and said auxiliary support member with sufficient clearance so that after one of said plate-like elements has been spaced from an adjacent plate-like element a sufficient distance, the first plate-like element can be swung out of its vertical plane until the lower notch clears the primary support member and can then be pivoted about said auxiliary support member out of engagement with the stabilizing member.
